UNITED STATES PATENT OFFICE.

RICHARD S. DAVIS, OF COLUMBIA, MISSISSIPPI.

PILE-POINT.

SPECIFICATION forming part of Letters Patent No. 748,705, dated January 5, 1904.

Application filed July 9, 1903. Serial No. 164,844. (No model.)

To all whom it may concern:

Be it known that I, RICHARD S. DAVIS, a citizen of the United States, residing at Columbia, in the county of Marion and State of Mississippi, have invented certain new and useful Improvements in Pile-Points, of which the following is a specification.

In driving board piles so as to form a slip inclosure or like structure considerable difficulty is experienced in alining the piles and causing their subjacent longitudinal edges to abut to provide a close joint.

This invention has for its object to overcome the aforesaid objectionable features and to insure the ready penetration of the pile into the bed of the stream or other formation when applying driving force thereto.

The invention consists, essentially, of a metallic point for ready penetration of the soil, said point being transversely inclined to insure lateral movement of the pile simultaneously with its advance, whereby a tight joint between adjacent piles is obtained. Ears project from one end of the point to embrace the edge portion of the adjacent pile to compel alinement of the piles without necessitating lateral prying or bracing, which is expensive and the source of no end of trouble.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a perspective view of a section of board piling embodying the invention. Fig. 2 is a side view of the lower or driving end of a pile. Fig. 3 is a vertical section on the line X X of Fig. 2. Fig. 4 is a perspective view of the pile-point, the dotted lines indicating the lower end portion of the pile. Fig. 5 is a perspective view of the pile-point as seen from the remote end of Fig. 4.

Corresponding and like parts are referred

to in the following description and indicated in all the views of the drawings by the same reference characters.

The pile-point is of metal and may be cast or fashioned from plate metal or otherwise constructed as found most advantageous. The point is oblong, the length depending upon the width of the pile for which the point is designed. The lower or penetrating end 1 of the point has its sides oppositely inclined and intersecting in an edge, which cleaves the soil as the pile is driven. Flanges 2 project upward from the penetrating end 1 and are spaced apart a distance corresponding, approximately, to the thickness of the pile, so as to receive the lower end thereof, as indicated most clearly in Fig. 3. The flanges 2 project at one end a short distance beyond the penetrating end 1, as shown at 3, to form guide extensions, which embrace opposite sides of the edge portion of the pile adjacent to the one being driven. This is shown most clearly in Fig. 1. The opposite end of the flanges 2 are set in from the proximal end 75 of the part 1 a distance corresponding to the projection of the extensions 3, so as to receive the latter when the piles are driven with their lower ends about in line, as indicated most clearly in Fig. 1. The cleaving portion of the point is inclined in the direction of the width of a pile upwardly and away from the pile previously driven, whereby the tendency of the point is to move the pile being driven toward the pile previously driven, thereby insuring a close joint between the piles, as will be readily comprehended. The pile being driven has the guide extensions 3 of its point embracing opposite sides of the last pile previously driven and which forms a guide for the pile being driven. The lower end of the pile is fitted between the flanges 2 and squarely upon the upper edge of the penetrating end and is secured to the point by fastenings passed through openings in the flanges 2 and through the lower end portion of the pile, as will be readily understood.

Having thus described the invention, what is claimed as new is—

1. A pile-point provided with guide extensions at one end for embracing opposite sides

of the pile previously placed in position so as to insure alining of the pile being driven, substantially as set forth.

2. A pile-point having spaced flanges for 5 security of the same to the lower end of a pile and having said flanges projected at one end to form guide extensions, substantially as described.

3. A pile-point comprising a penetrating 10 end and spaced flanges set in from one extremity of the penetrating end and projecting from the opposite extremity to said penetrating end to form guide extensions, substantially as specified.

15 4. The herein-described pile-point of ob-

long formation and having its penetrating end inclined throughout its length and its sides oppositely beveled and spaced flanges projected from the upper edge of the penetrating end and set in from one extremity of the 20 penetrating end and projected a corresponding distance from the opposite extremity of the penetrating end to form guide extensions, substantially as set forth.

In testimony whereof I affix my signature 25 in presence of two witnesses.
